United States Patent Office

Des. 187,714
Patented Apr. 19, 1960

187,714

WEATHER INSTRUMENT OR SIMILAR ARTICLE

Howard S. Taylor, Fox River Grove, Ill., assignor to
Airguide Instrument Company, Chicago, Ill., a corpora-
tion of Illinois

Application December 14, 1959, Serial No. 58,648

Term of patent 14 years

(Cl. D52—7)

Fig. 1.

Fig. 2.

Fig. 3.

Fig. 4.

Fig. 1 is a front elevational view of a weather instru-
ment or similar article showing my new design;

Fig. 2 is a top plan view thereof;

Fig. 3 is a rear elevational view thereof; and

Fig. 4 is a right-hand elevational view thereof.
The dominant features of the design are shown in
full lines.

I claim:

The ornamental design for a weather instrument or
similar article, as shown and described.
